UNITED STATES PATENT OFFICE.

WILLIAM F. LAUTENSCHLAGER, OF CINCINNATI, OHIO, ASSIGNOR TO LORENZ MUTHER,
OF NEWTON, MASSACHUSETTS.

FOLDING-MACHINE.

1,207,941.

Specification of Letters Patent. Patented Dec. 12, 1916.

Application filed June 26, 1916. Serial No. 105,930.

To all whom it may concern:

Be it known that I, WILLIAM F. LAUTENSCHLAGER, a citizen of the United States, residing in Cincinnati, in the county of 5 Hamilton, State of Ohio, have invented certain new and useful Improvements in Folding-Machines, of which the following is a specification, reference being had to the drawings accompanying the same and forming 10 a part thereof.

My invention relates to folding machines for folding the edges of sheet material, such as boot and shoe parts, and vamps, both open and closed, and the like.

15 The objects of my invention are as follows:—To provide an operating connection for slitting knives, and the like, so constructed that it will be directly connected to the slitting knife, or other devices, at all 20 times, and yet so constructed and arranged that the slitting knife may be moved to an inoperative or stationary position when not slitting the material.

A further object of my invention is to so 25 construct and arrange the operating connection that by a slight change in the location and method of attaching a controlling spring, the knife, or device to be operated, may be set or positioned to be either normally 30 operative or normally inoperative, as desired, and to provide means under the control of the operator so that when said connection is attached to a slitting knife, he can at will cause the knife to cut or not cut. 35 This control of the operation of a slitting knife is desirable because of the fact that when the operating connection is used in a folding machine it is not desirable to cut the edge of the work where convex curves 40 or seams occur, particularly on boot or shoe parts; and further, it is considered by some manufacturers undesirable to cut or snip the edges being folded at straight portions of boot and shoe parts. With my operating 45 connection, the operator can cut or not cut the edges of the material being folded whenever and whenever he desires.

Heretofore, in machines where the slitting knife has been directly connected with 50 the operating mechanism, the upper slitting knife has been of the constantly reciprocating or oscillating type. In such type of machine there has always been a tendency to mar or cut the edge of the work, particularly where seams occur, due to the con-

tinuous moving of the knife when not designedly in cutting position. Such tendency to cut or mar the work is entirely eliminated by my improved operating connection because of the fact that the slitting knife when not in use is stationary.

The improvements herein described are shown as applied to a folding machine such as forms the subject-matter of my application filed June 21, 1911, Serial No. 634,485, 65 wherein the frame of the machine is constructed with two overhanging arms projecting horizontally from a base and upright forming the support for the machine, the lower overhanging arm constituting the 70 work-support, its end being of small cross section,—what has been termed by some “cylinder form,” so as to furnish a narrow work-support which will permit the folding of what is known or termed “closed vamps.” 75 This machine is also provided with a removable table so that when the removable table is attached, flat or open vamps may be readily folded.

In the drawings accompanying this specification and forming a part thereof—Figure 1 is a side elevation of a folding machine having my improvements incorporated therein and showing a section of the removable table; Fig. 2 is a sectional plan view 85 taken through line 2—2 Fig. 1 showing a plan of the work-support or lower overhanging arm; Fig. 3 is a sectional end view taken on line 3—3 Fig. 1, with the standard and upright in the rear thereof eliminated 90 and the removable table broken away; Fig. 4 is a sectional side view taken on line 4—4 Fig. 3; Fig. 5 is a sectional side view of the slitting mechanism and its connections taken on line 5—5 Fig. 3; and Fig. 6 is a view, 95 the same as shown in Fig. 5, except that it shows the mechanism for operating the slitting knife adjusted to its non-operative position as the parts have been assembled for the purposes of illustrating the invention. 100

In the drawings, 1 represents the rear standard of the folding machine, and 2 the base for securing it to the bench or support on which the machine is to be mounted.

3 is the upper overhanging arm upon 105 which is mounted the feeding mechanism and the presser-foot.

4 is the lower overhanging arm upon which is mounted the fold-block, slitting 110 knife and the fold-presser.

The various mechanisms are operated by a shaft 5 which extends through the standard 1 and has bearings in the lower overhanging arm 4. A pulley 6 is mounted on the end of the shaft 5 and is grooved at 7 to take a belt for operating the machine.

The feeding elements of the machine are operated by the shafts 8 and 9 which have bearings in the upper overhanging arm 3. 10 The feeding members comprise a reciprocating four-motioned feed-foot 10 which has a 15 slideable bearing in the rockable bearing 11. The rockable bearing 11 is secured by a clamping member 12 and the clamping screw 18 to the end of the shaft 8. The backward and forward movement of the feed-bar 10 is 20 imparted to it by the oscillating movement of the shaft 8. The upward and downward reciprocating movement of said feed-foot 10 is 25 imparted to it by the oscillating movement of the shaft 9. The shafts 8 and 9 are oscillated by means of eccentrics 14 and 15 inside of the bearings on the connections 16 and 17, as described in my application, Serial No. 634,485.

The upward and downward movements to the feed-foot 10 are imparted to it by the connection 18 secured at one end to the oscillating shaft 9, its other end secured by the 30 pivot 19 to an upright forked member 20 which engages a member 21 formed on the collar 22, the collar 22 being split on one side and retained in place by the binding screw 23. The oscillations of the shaft 9 35 imparted to the link 20 and thence through the stud 21 and collar 22 serve to lift and lower the feed-bar 10. On the lower end of this feed-bar 10 there is formed a feed-foot 24, which as it is moved to the right in Fig. 40 3 and downward, engages the material, and as it moves to the left in Fig. 3, feeds the material forward, and is disengaged from the material when lifted by oscillation of the shaft 9.

45 25 is a presser-foot which is designed to move downwardly through movement of the shaft 9, and engage the material just previous to the lifting of the feed-foot 24, and is lifted and disengaged from the material just previous to the feeding movement of the feed-foot.

50 Instead of a lower idler roll, as employed in my application Serial No. 634,485, I employ in this machine what I might term an idler plate 26 which is free to move backward and forward with the feeding movement of the feed-foot 24. It is mounted on the rolls 27, 27, which have a bearing on the screws 28, 28, secured in the end of the frame 4. 55 This idler-block is formed to move laterally with the material as it is being fed. Immediately on the feed-foot 24 releasing its hold or pressure upon the material the idler-block 26 moves to the right, as shown in Fig. 3, 60 this movement being accomplished by means

of a compressible spring 29 mounted in the work-support and bearing against this idler-block.

The edge-turning block 30 for turning over the edge of the material is of the type 70 as employed in my said application, Serial No. 634,485, of June 21, 1911, heretofore referred to. The fold-presser 31 is of the type 75 as shown and described in my application of June 26, 1916, Serial No. 105,929, and is shown in cross section Fig. 4, and need not be more fully described.

My improved slitting knife and its operating mechanism is clearly illustrated in Figs. 5 and 6. In Fig. 5, the knife and its operating mechanism is shown in a cutting position, or in a position to operate the slitting knife. The slitting knife 32 is preferably slotted at 33 and secured by a binding screw 34 to an oscillating lever 35 in such 85 manner as to have a constant bearing against the lower cutting-block 55. The oscillating lever 35 has a bearing on the shaft 36 so as to be oscillated thereon. This lever 35 has an extension 37 which is pivoted to the connection 39 by the pivot 38, the connection 39 having a circular bearing 40 which is cut away at one side and is mounted upon the circular bearing 41. This circular bearing 41 is formed upon the side of a plate 42. 95 The plate 42 is provided with a semicircular elongated slot 43 formed therein, the slot 43 extending through the side of the circular bearing 41. The plate 42 is pivoted to an oscillating lever 44 by the pivot screw 45 so 100 that it may be partially rotated upon said pivot screw 45. The lever 44 is movably mounted at its center upon the shaft 46, which has a bearing in the lower arm 4 of the machine. The location of the shaft 46 105 is shown in Fig. 1 and again in Fig. 4.

The lever 44 is oscillated by a crank member 47 secured upon the outer end of the shaft 5. This crank member has a crank-pin 48 which is rotatively secured in the block 49. The block 49 has a pivot shaft 50 extending through it so as to pass through the hole 51 in the lever 44. Rotation of the crank member 47 causes a rotative movement of the pin 48, block 49 and the pivot member 50. The pivot member 50, however, always remains in a substantially horizontal position, due to the fact that the pin 48 is mounted so as to revolve in the block 49. The revolving movement of the crank 47 causes an up and down, or oscillating movement of the ends of the lever 44. As viewed in Fig. 5, this oscillating movement of the lever 44 on the bearing 46 causes an oscillation of the pivot 45 and through said pivot the oscillation of the plate 42 and the projecting circular bearing 41 formed on the side thereof. This oscillating movement, when the plate 42 is moved to the right hand end of the slot 43, as shown in Fig. 5, causes 130

the oscillation of the circular bearing 41, and through it imparts an endwise movement to the connection 39 and to the rocking lever 35 through the pivot 38 and its bearing 36 and this causes an oscillating or up and down movement to the cutting edge 52 on the knife 32.

The plate 42 has attached to it at 53 a rod 54 which may be connected to a treadle, not shown, so that downward pressure upon the treadle would rotate the plate 42 on the pivot 45 to a position as shown in Fig. 6, thus throwing the circular bearing 41 so that its periphery is concentric with the axis of the shaft 46. When the bearing 41 is concentric with the shaft 46, rocking movement of the lever 44 will simply tend to partially rotate the bearing 41 around the axis of the shaft 46 and produce no endwise movement on the connection 39, so that while the parts are positioned as shown in Fig. 6 there will be no movement of the rocker-lever 35 and the knife 32.

It will be seen that notwithstanding the parts connecting the knife 32 with the crank 47 on the end of the shaft 5 are at all times directly connected, yet when the plate 42 and the bearing 41 are positioned as shown in Fig. 6, there is positively no movement to the knife 32 and it is held in its upward position, as shown in Fig. 6, and stationary.

As shown in Fig. 5, as the crank 47 rotates, the pivot 50 will move downward. Such downward movement of the pivot 50 will rock the lever 44 and throw the pivot 45 upwardly and the plate 42 and bearing 41 on it upwardly. The circular bearing 41 will have a rotative movement in the bearing 40 of the connection 39 and a lateral movement as well to move said connection 39 upwardly and oscillate the lever 35 on the pivot 36, drawing the knife 32 downwardly and its cutting edge 52 into a scissors-like shearing contact with the cutting edge of the lower cutting block 55, thereby forming slits in the edge of the material as it is fed forward, the movement of the slitting knife 32 when positioned as shown in Fig. 5 occurring at each feeding movement of the material. Likewise, there is a movement of the fold-presser 60 at each feeding movement of the material, the fold-presser 60 being pivoted on the shaft 36, which is the same pivot point as the lever 35 is pivoted upon, the fold-presser having formed on its lower end a downwardly extending portion 61 having preferably a forked slot 62 which embraces a pivot 63 mounted in the end 64 of a rocking-lever which in turn is mounted upon the bearing 46. This rocking-lever 64 has the portion 65 which is pivoted to the bearing 50 which is mounted in a block 49, which in turn is pivoted upon the pivot or crank-pin 48 secured in the crank 47, so that the up and down move-

ment of the pivot 50 heretofore described causes an up and down movement of the end 65 of the lever 64 and an oscillating movement to the pivot 63, which oscillating movement is communicated through the slotted portion 62 and downwardly extending portion 61 to rock the fold-presser 60 upon the bearing 36. The fold-presser 60 is extensible, or capable of being moved in and out upon the bearing portion 66, and is held in inward position by the spring 67, as shown, the presser 60 being moved outwardly by means of the lever 68, the end 69 of which bears against the curved portion 70. This lever 68 has an extending portion 71 which extends downwardly under the removable table 72 so as to be easily manipulated by the operator.

As shown in Fig. 5, the plate 42 is held in the position shown in said figure by means of a spring 75 which may be made to fit around the pivot 45 with one end fastened to the plate 42, as at 76, the other end being bent around the portion 77 of the lever 44 so that the extensible action of the spring 75 will hold the plate 42, as shown in Fig. 5. The adjustment of the knife to a stationary or non-operating position is made against the tension of this spring, as shown in Fig. 6.

I do not desire to limit my invention to the exact form illustrated and described, or to its application to a slitting knife, or to an oscillating slitting knife. The illustration and description in this specification are intended to show a useful application of my invention. It may, however, be applied to other types of machines, and to reciprocating, as well as oscillating slitting knives, without departing from the spirit of my invention.

What I claim is—

1. In a folding machine, the combination of feeding and folding means, of a slitting knife and means for operating it directly connected to said slitting knife, said operating means comprising a lever, a plate pivoted to said lever, a bearing formed on the side of said plate, a pivot-shaft for said bearing, said plate and bearing having an elongated hole, one end of the hole being concentric with said bearing and the other end extending outside of the periphery of said bearing, a connection mounted at one end on said bearing and its other end pivoted to a knife operating lever, said knife operating lever, the slitting knife being mounted upon the free end of said operating lever, and means for moving the first-mentioned bearing to a position either concentric or eccentric to the shaft upon which it is pivoted to render the slitting knife movable to cut, or stationary and non-cutting.

2. In a folding machine, operating mechanism for a slitting knife, a slitting knife, a

connection for the slitting knife pivoted at one of its ends to the operating mechanism and at its other end to the slitting knife, and a pivoted bearing in said operating mechanism, so formed and arranged that the bearing may be adjusted to positions either concentric or eccentric to the axis on which it is pivoted, as desired, so as to render the slitting knife either inoperative and stationary, or operative and in a cutting position.

3. In a folding machine having a slitting knife, means for operating said slitting knife, comprising an oscillating lever, a pivot on which said lever oscillates, a member movably mounted on said lever, a bearing on said movable member, means for adjusting said bearing to positions either eccentric or concentric with relation to said pivot, and means for oscillating said lever.

20 4. In a folding machine, a slitting knife, operating means for the slitting knife, a connection pivoted at one end to the slitting knife, its other end being pivoted upon a bearing in the operating means, means for oscillating said bearings, and means for adjusting said bearing to positions either eccentric or concentric with relation to the pivot upon which it oscillates to render the slitting knife either operative or inoperative 30 as desired.

5. A folding machine having a slitting mechanism comprising a stationary knife and a movable knife, the movable slitting knife being so arranged upon an oscillating lever as to have a constant bearing against said stationary knife and so that the cutting edges of said knives will pass each other and operate with a scissors-like action, said oscil-

lating lever, operating means for operating the oscillating lever, a connection for connecting the oscillating lever and the operating means, and means whereby the pivot on the operating means to which the connection is pivoted may be adjusted so as to render the slitting mechanism either operative or 45 inoperative, as desired.

6. In a folding machine, means for feeding the material, means for folding over the edge of the material, means for pressing the folded edge, comprising a fold-presser having a fold-presser surface movable longitudinally of the fold-presser, a slitting knife, and operating means for the slitting knife, directly connected thereto, said operating means having a pivoted bearing so formed 55 and arranged that it can be adjusted to positions either eccentric or concentric to the axis upon which it is pivoted to render the slitting knife either operative or inoperative and stationary, as desired.

60 7. A folding machine having means for feeding and folding over the material combined with a slitting knife, and means for operating the slitting knife, comprising an oscillating member, means for pivotally connecting said oscillating lever and the slitting knife, means for adjusting said connection with relation to the bearing of the oscillating lever to render the slitting knife operative or inoperative, as desired, and means 65 for oscillating the oscillating lever.

In testimony whereof, I have hereunto set my hand, this the 23rd day of June, A. D. 1916.

WILLIAM F. LAUTENSCHLAGER.
